CLAIM

The ornamental design for a saw blade, as shown and described.

DESCRIPTION

Cross reference is made to copending U.S. design patent application Ser. No. 29/555,203 entitled "Saw Blade" by Fellmann et al. filed on even date herewith; U.S. design patent application Ser. No. 29/555,211 entitled "Saw Blade" by Butscher et al. filed on even date herewith; and U.S. design patent application Ser. No. 29/555,214 entitled "Saw Blade" by Fellmann et al. filed on even date herewith.

FIG. 1 is a perspective view of a saw blade, showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom view thereof.

The broken lines shown in the drawings illustrate portions of the saw blade that form no part of the claimed design. The area lined with lines oriented in one direction and the area lined with lines oriented in another direction possess contrasting colors in relation to each other. The lines of the lined areas form no part of the claimed design, but rather are included merely to define the locations of the lined areas. It is to be understood that the contrasting colors are not limited to the colors specifically indicated in the drawing disclosure. The area lined with lines oriented in one direction and the area lined with lines oriented in another direction illustrate a contrast in appearance.
